UNITED STATES PATENT OFFICE.

FRANCIS M. LECHNER, OF COLUMBUS, OHIO, ASSIGNOR TO WILLIAM V. BAKER, OF SAME PLACE.

BALL-BEARING.

SPECIFICATION forming part of Letters Patent No. 615,070, dated November 29, 1898.

Application filed March 5, 1898. Serial No. 672,794. (No model.)

To all whom it may concern:

Be it known that I, FRANCIS M. LECHNER, a citizen of the United States, residing at Columbus, in the county of Franklin and State of Ohio, have invented a certain new and useful Improvement in Ball-Bearings, of which the following is a specification.

My invention relates to the improvement of ball-bearings, and has particular relation to that class of ball-bearings adapted for use in connection with vehicle-spindles, although the same may be employed for other purposes.

The objects of my invention are to provide an improved construction of independent bearing-ball-holding cages, to provide improved means for inserting and retaining the balls within said cages, to provide improved means for the adjustment of the balls within the bearing, and to produce other improvements which will be more specifically pointed out hereinafter. These objects I accomplish in the manner illustrated in the accompanying drawings, in which—

Figure 1 is a central longitudinal section of the spindle-boxing and ball-cages therein, the spindle being shown in elevation; and Fig. 2 is a face view of one of said ball-cages.

Similar letters refer to similar parts throughout both views.

30 *a* represents the boxing which I employ about the spindle, said boxing being of a general cylindrical form and having an enlarged inner end portion *a'* and outer end portion *a''*. Within the enlargement *a'* I provide an internal shoulder *b* and within the enlargement *a''* a similar shoulder *b'*.

Each of the ball-holding cages, which I employ in the manner hereinafter described, is constructed as follows: *c* represents an internal ring or cage section, on the periphery of which is formed a continuous raceway or ball-groove *c'*. This ring *c* is surrounded or encircled at a distance therefrom by an external ring or cage section *d*, the latter being provided on its inner surface with a raceway or groove *d'*. As indicated in the drawings, the bearing-balls *e* are adapted to bear and run in said raceways and between said ring-sections *c* and *d*. In order to insert the balls 45 into the raceways and between the ring-sections, I have provided the outer ring-section

d on its inner surface and on one side thereof with an inlet notch or recess *f*, which is preferably in the arc of a circle shown, and on the corresponding side and in the outer surface 55 or periphery of the inner ring *c* I have provided a similar recess *f'*. When the rings are so turned that these recesses are opposite each other, it is obvious that said recesses, in conjunction with the space between the rings, 60 may provide an opening sufficient for the insertion within the raceways of the balls *e* one at a time.

In the construction of the spindle *g*, upon which the ball-cages herein described are 65 adapted to be employed, I provide the usual inner peripheral shoulder *g'* at the junction of the spindle and axle-body, and on the outer side of this shoulder at a suitable distance therefrom I provide said spindle with 70 a threaded portion, (indicated at *g''*.) The boxing *a* is adapted to have screwed into the end of the inner end enlargement *a'* a ring-plug *h*, while a similar plug *h'* is adapted to be screwed into the outer enlarged end portion 75 *a''* of the boxing.

In mounting the ball-cages on the spindle the ring-plug *h* is first slipped over onto the axle-body or its shoulder *g'*. The ball cage or cages which are adapted to be employed 80 about the inner end of the spindle are then slipped onto the spindle until the inner ring *c* of the inner cage abuts against the spindle-shoulder *g'*. In case two of said cages are to be used about said inner spindle end the second cage is similarly slipped onto the spindle until its inner ring-section abuts against the inner ring-section of the first cage. Prior to the placing of said second cage, however, I slip over the spindle a separating-ring *i*, which 85 is adapted, as shown, to be retained between the balls of the two cages. This separating-ring, however, may only be used when two cages are employed, and where two adjoining cages are thus employed those sides of the 90 cages in which the recesses *f f'* are formed are made to adjoin each other. The cages being thus made to surround the inner end portion of the spindle, I screw upon the threaded portion *g''* of said spindle a nut *k*, the latter being turned to abut against the outer surface 95 of the inner ring *c* of the outer cage. This

being accomplished, the boxing *a* may now be slipped over the spindle until its internal shoulder *b* is in contact with the outer ring *d* of the second ball-cage. The ring-plug *h* may now be screwed into the inner end of the boxing enlargement until it is in contact with the outer ring *d* of the first cage.

The outer cage, or that ball-cage which is employed about the outer end of the spindle, is constructed in the manner hereinbefore described, with the exception that the outer ring *d* of said cage is externally threaded to admit of its being screwed into the outer internally-threaded portion of the boxing enlargement *a*² until said outer ring abuts against the shoulder *b'* and the inner ring *c* abuts against a shoulder *g'* of the spindle. This outer ball-cage is so inserted within the boxing as to bring its ball-inlet recesses *f* and *f'* on the outer side, and in order to prevent any possibility of the balls or any one of them escaping through said recesses by reason of the cage-rings becoming so turned as to bring said recesses opposite each other I have formed the outer spindle-nut *n*, which screws upon the outer threaded end of the spindle after the insertion of said cage, with a shallow inturned flange, which is indicated at *o*, said flange projecting over the outer side of the inner cage-ring *c*. This being accomplished, the outer cap-nut *h'* is screwed into the boxing end until it abuts against the outer cage-ring *d*.

In case but one of the ball-cages is employed in the inner end of the boxing it is obvious that the nut *k* may be provided with the flange projection *o* shown on the nut *n*.

From the construction which I have described it will be seen that the ball-cages are formed entirely independent of each other and that by so turning the inner and outer rings of each cage as to bring the recesses *f* and *f'* out of alinement with each other said cages may be produced and handled prior to their connection with the spindle without danger of the balls escaping therefrom.

In case the frictional contact of the balls with the raceway surfaces should result in undesirable wear or throw the balls on said surfaces it is obvious that an inward adjusting movement may be imparted to the inner rings of the ball-cages by turning up the nuts *k* and *n*. An adjustment of the outer cage-section *d* in the opposite direction from that above described may be effected by temporarily removing the cap-nut *h'* and turning outward the outer ring *d* the desired distance. An adjustment in a similar direction of the outer rings of the inner cages may like-

wise be effected by turning inward the ring-lug *h*. It will thus be seen that not only are superior means provided for the construction and arrangement of the ball-supporting cages, but that the sections forming the cages may be adjusted in opposite directions to compensate for wear.

Having now fully described my invention, what I claim, and desire to secure by Letters Patent, is—

1. In a ball-bearing, a ball-cage consisting of an outer and an inner ring-section, there being a continuous groove or raceway on the inner face of the outer section, a similar groove or raceway on the outer face of the inner section, and recesses *f* and *f'* formed in corresponding faces of said outer and inner sections, said recesses adapted to be brought opposite each other and balls between said ring-sections, substantially as and for the purpose specified. 70

2. In a ball-bearing, the combination with a spindle, and boxing about the same and a shoulder on said spindle, of a ball-holding cage consisting of an outer and an inner ring-section, there being oppositely-located raceways in said sections and recesses as described in said ring-sections, said ball-cage adapted to surround said spindle and bear against said shoulder, balls between the ring-sections and a nut adapted to screw onto said spindle and abut against said inner ring-section, said nut having an inturned flange *o* thereon adapted to project within the space between said ring-sections, substantially as and for the purpose specified. 85

3. In a ball-bearing, the combination with a spindle, there being a shoulder *g'* and a threaded portion *g*² on said spindle, a boxing surrounding said spindle having an enlarged inner end portion and an internal shoulder in said boxing enlargement, of a pair of ball-holding cages mounted on said spindle, the inner cage abutting against said shoulder *g'* and each of said cages consisting of an outer and an inner ring-section having oppositely-located raceways, balls in said raceways there being ball-inlet recesses *ff'* formed as described in said ring-sections, a separating-ring *i* between the balls of said cages, a nut *k* on said spindle-threaded portion and a ring-plug *h* adjustably engaging with the inner end of the boxing, substantially as and for the purpose specified. 105

FRANCIS M. LECHNER.

In presence of—

C. C. SHEPHERD,
EDWARD M. TAYLOR.
